ELECTRIC REMOTE CONTROLLER CASING

Filed March 20, 1939

INVENTOR.

Lloyd J. Andres

UNITED STATES PATENT OFFICE

115,306

DESIGN FOR AN ELECTRIC REMOTE CONTROLLER CASING

Lloyd J. Andres, Chicago, Ill., assignor to Automatic Instrument Company, Grand Rapids, Mich., a corporation of Michigan

Application March 20, 1939, Serial No. 83,715

Term of patent 7 years

To all whom it may concern:

Be it known that I, Lloyd J. Andres, a citizen of the United States and resident of Chicago, in the county of Cook and State of Illinois, have invented a new, original, and ornamental Design for an Electric Remote Controller Casing, of which the following is a specification, reference being had to the accompanying drawing, forming part thereof.

The figure is a perspective view of the electric remote controller casing, showing my new design.

I claim:

The ornamental design for an electric remote controller casing, as shown.

LLOYD J. ANDRES.
